Primary Examiner — Marianne Pandozzi(74) *Attorney, Agent, or Firm* — Browdy and Neimark, PLLC(57) **CLAIM**

The ornamental design for a coffee dripper, as shown.

DESCRIPTION

FIG. 1 is a front elevational view of a coffee dripper showing my new design;

FIG. 2 is a rear elevational view thereof;

FIG. 3 is an enlarged detail showing a portion of the surface pattern taken along lines 3A-3A and 3B-3B of FIG. 1;

FIG. 4 is a left side elevational view thereof;

FIG. 5 is a right side elevational view thereof;

FIG. 6 is a top plan view thereof;

FIG. 7 is an enlarged sectional view taken along line 7-7 of FIG. 6;

FIG. 8 is a bottom plan view thereof;

FIG. 9 is a perspective view thereof, viewed from above; and,

FIG. 10 is a perspective view thereof, viewed from the bottom.
